Primary Examiner — Celia Murphy*Assistant Examiner* — Jennifer L Rempfer(74) Attorney, Agent, or Firm — Crossley Patent Law(57) CLAIM

The ornamental design for a long sleeve scrub top, as shown and described.

DESCRIPTION

FIG. 1 is a front elevation view of a long sleeve scrub top showing my new design;

FIG. 2 is a rear elevation view thereof;

FIG. 3 is a right side elevation view thereof, the opposite side being a mirror image of the shown;

FIG. 4 is a top plan view thereof; and,

FIG. 5 is a bottom plan view thereof.

The broken lines represent stitching.
